UNITED STATES PATENT OFFICE.

JULIUS EGGERS, OF CASSEL-WILHELMSHÖHE, AND PETER THOMSEN, OF CASSEL, GERMANY, ASSIGNEES, BY MESNE ASSIGNMENTS, TO LOCOMOTIVE SUPER-HEATER COMPANY, A CORPORATION OF DELAWARE.

COMBINED MARINE WATER-TUBE BOILER AND SUPERHEATER.

1,316,701.

Specification of Letters Patent. Patented Sept. 23, 1919.

Application filed February 21, 1916. Serial No. 79,632.

To all whom it may concern:

Be it known that we, JULIUS EGGERS and PETER THOMSEN, both citizens of the German Empire, residing, respectively, at Cassel-Wilhelmshöhe, and at Cassel, Germany, have invented a new and useful Combined Marine Water-Tube Boiler and Superheater, of which the following is a specification.

In marine water tube boilers especially such with flue tubes of restricted cross section, one upper drum and two or three lower drums, and with a superheater arranged in the last lateral flue at the side of the water tubes, there is a particularly great necessity to dispose within the comparatively small flue space a large superheating surface in such a manner that no water- or air pockets can arise during the more or less long service interruptions, for instance, in a harbor.

Besides this condition, certain others require fulfilling, viz., maintaining the counter current, as well as the possibility of fastening the superheater pipes without special supports, and to shape and arrange them in such a way that they may be conveniently connected at their upper ends with the upper drum or the wet steam distributor and at their lower ends with the superheated steam collector.

Among the various forms of construction of superheaters as employed in connection with boilers of the kind in question there are also such consisting of a plurality of flat coils which are connected in parallel and are so arranged that the coils are located in vertical planes standing crosswise to the longitudinal axis of the boiler. Such superheater pipes are made use of also in the present case, but the shape of these

pipes is such that the formation of air- and water-pockets is prevented even if the vessel is inclined in a certain degree to one or the other side, that shape being moreover such that a great superheating surface can be disposed in the respective flue. Each of

these superheating pipes is zig-zag-shaped, but the two pipe sections belonging to, and forming, any one of the acute angles of an individual superheater pipe are of different length; the shorter legs and the longer ones alternate with each other; the shorter legs are inclined downwardly in the direction of the adjacent set of the water tubes of the boiler, and the longer ones are inclined in

the direction to the outer shell of the boiler, as is all more fully described hereinafter and shown, in two forms of construction, in the accompanying drawing in which:

Figure 1 is a diagrammatical representation of a cross section through a water tube boiler provided with our improved superheater, the boiler having in this instance three lower drums; and

Fig. 2 is a similar representation of a boiler having but two lower drums, and the superheater being slightly changed.

In both forms of the invention the fire gases washing the superheater pass in upward direction, the steam, however, flows through the superheater pipes in downward direction, so that the counter current principle is maintained. Further, in both forms the superheater consists of two sets of individual superheater pipes or elements which alternate with each other lengthwise of the boiler in such a manner that each short leg of any one of the zig-zag-shaped flat coils crosses the neighboring two long legs of the neighboring two flat coils, and the same is true of the long legs of the first-named coil and the short ones of the neighboring two.

Apart from the differences between Figs. 1 and 2 that Fig. 1 has three lower drums, Fig. 2, however, but two, there are the further two differences between said figures that, first, in Fig. 1 the flat coils are each single, whereas in Fig. 2 double coils are employed, i. e., each individual superheater element is made up of two pipe lengths laid side by side in a plane transverse to the boiler axis and bent as one in zigzag fashion with alternating short and long legs as described for the single pipes of Fig. 1; second, in Fig. 1 the whole of each coil has an oblique position, whereas in Fig. 2 only the lower part is so disposed.

Referring to Fig. 1, b is the upper drum, from which extend the zigzag shaped flat coils a' a² consisting each of short portions or legs a', and of long portions or legs a² which alternate with each other. The legs a' are inclined downwardly in the direction of the adjacent boiler tubes; the legs a² are inclined downwardly to the other side, and the flat coil as a whole is inclined parallel to said boiler tubes, as shown. The upper ends of the thus shaped and located flat coils, or superheating tubes respectively, are

connected with the drum *b*, receiving from this latter the saturated steam, the lower ends are connected with a superheated steam collector *c* from which the superheated steam *d* is led to the engine. *d* is the inclosing shell of the boiler. It is obvious that neither the condensed steam arising at times within the superheating pipes, nor the air separating from the steam can form a pocket or pock-
10 ets, even if the vessel is tilted from its normal position. And it is further obvious that owing to the crosswise arrangement of the short and long legs of the neighboring superheater pipes, and, as a consequence of
15 this arrangement, owing to the direct contact made possible between the neighboring pipes at the places of crossing, a larger number of the flat coils may be disposed in the flue, because no space need be left between
20 two such coils or pipes, the fire gases washing nevertheless the whole surface of each of them.

Referring to Fig. 2, each vertical superheating pipe plane contains two such pipes
25 which run parallel to one another throughout their whole length. The axis of each flat double coil, in its upper part, does not extend obliquely but vertically, and the upper ends of the pipes are not connected imme-
30 diately with the drum *b*, but with a saturated steam distributor *f* which is, in its turn, connected with said drum by means of a pipe *g*. The lower pipe ends are connected with a superheated steam collector *c*, just as
35 in Fig. 1.

Having now described our invention what we desire to secure by a patent of the United States is:

The combination, with a water tube boiler having laterally disposed upper and lower drums connected by water tubes, and a flue adjacent to and outside of said tubes, of a plurality of zig-zag shaped superheater elements in said flue each element comprising a plurality of shorter sections inclined downwardly in the direction of the neighboring water tubes, and a plurality of longer sections alternating with said shorter ones and inclined downwardly away from said water tubes; each element being bent in a plane transverse to the boiler axis and the axis of each element being substantially parallel to the direction of the water tubes; neighboring elements, furthermore, being mutually shifted axially with respect to one another so as to make the shorter sections of any element cross the longer sections of its neighboring element in the axial plane of the element, said elements being in contact at such crossing, substantially as described and shown.

In testimony whereof, we have hereunto set our hands in the presence of two subscribing witnesses.

JULIUS EGGER.
PETER THOMSEN.
